UNITED STATES PATENT OFFICE

2,574,852

HUMIDIFYING APPARATUS

Sven W. Wallin, Jonkoping, Sweden, assignor
to A. B. Svenska Flaktfabriken, Stockholm,
Sweden

Application September 27, 1946, Serial No. 699,670
In Sweden June 20, 1945

5 Claims. (Cl. 261—90)

1

The present invention relates to a method for humidifying of air or gas and an apparatus for carrying out the method.

In the process of humidifying of air apparatus are known per se which consist of a rotatable disc for receiving liquid and a fan driving air to be humidified towards the disc. The present invention relates to apparatus of this kind.

The method according to the invention is mainly characterized in rotating the disc and thereby bringing the liquid on it to be thrown out in a thin film substantially in right angles to the direction of flow of the air to be humidified and forcing the air through this film.

The invention is made clear in the accompanying drawings and by way of the following description.

Referring to the drawings:

Figure 1 is a diagrammatical front view of an apparatus according to the invention;

Figure 2 is a section on the line II—II of Figure 1;

Figure 3 is a part of Figure 2 on an enlarged scale;

Figure 4 is a vertical section on the line IV—IV of Figure 2.

In Figures 1 and 2, 1 designates an annular member fixed to a shell or tube 2 and two supporting legs 3 and 4 which latter support an electrical motor 5. A fan-wheel 6 is mounted on the shaft of the motor 5, and has an imperforate hub portion 6a surrounded by flange 18 which extends therefrom. This hub compels the air to flow between the tube 2 and the flange 18 in a stream which is annular in cross section. The shell 2 is provided with two parallel ears 7 (one of them only is shown in Figure 1) in which a supporting member or sleeve 8 is swingably journaled on a pin 7a parallel with the motor axis and, seen in the direction of the flowing air, situated in front of the fan-wheel 6. A spindle 9 is journaled in two antifriction bearings 10 and 11 mounted in the supporting member 8 which consists of a supporting arm 8a and a central annular part 8b (see Figure 4). The one end of the spindle 9 supports a disc 12 and the other a friction-wheel 13. The central part 8b of the supporting member 8 further supports a swingably mounted pin 14 which is provided with stub shaft 15 (Figure 3) the free end of which supports a friction-disc 16 journaled on the stub shaft 15 by means of an anti-friction bearing 17. The supporting member 8 is positioned relative to the flange 18 of the fan-wheel 6 in such a way as to locate the friction-wheels 13 and 16 inside the

2

flange 18. The flange 18 is provided with an internal annular track 19 on which the frictional wheel 16 rolls when in operation. By this arrangement the disc 12 will be driven from the fan-wheel 6 through the spindle 9 and the friction-wheels 13 and 16, and track 19, as soon as the fan-wheel is put in rotation. Owing to the great difference in diameter between the track 19 in the flange 18 and the wheel 13, the disc 12 always will rotate with a greater number of revolutions than the fan-wheel.

The friction-wheels 13 and 16 are pressed towards the track 19 in the flange 18 by the weight of the supporting member 8 and the disc 12, which are pivoted on the spindle 7a in ears 7. If the weight of the parts does not press together the friction surfaces of track 19 and wheels 13 and 16 with sufficient force, the frictional contact may be increased by turning wingnut 22 on bolt 20 23 fixed to the shell 2 to compress spring 20 against boss 24 on arm 8a. If the weight of the parts is too great, the frictional contact may be decreased by locating the spring between the shell 2 and boss 24 to counteract the weight of the parts.

The arm 8a of the supporting member is preferably hollow and supports a pipe 25 intended for supplying water or another liquid to the disc. The pipe 25 is bent in the manner that it extends to the right hand end of the spindle 9 (Figures 2 and 3), which end is of a special shape facilitating spreading of the liquid on the disc 12. The water is preferably supplied to the pipe 26 through a flexible tube 26 communicating with a reservoir, not shown in the drawing. That reservoir is preferably in known manner provided with automatic acting regulating means.

The embodiment above described is an example only for carrying out the invention. The disc 12 may also be brought to rotate by a separate drive-motor preferably positioned on a fixed support. The drive-motor may in this case preferably be arranged so that the number of revolutions of the disc 12 may be regulated. The regulation of the number of revolutions of the disc may also be performed in such a manner that the disc is driven by a friction-gear with variable gearing.

What I claim as new and desire to secure by Letters-Patent is:

1. Apparatus for humidifying air comprising a tube, open at both ends, a propelling fan and motor fixedly connected to said tube and having a hub member thereon, a disc substantially coaxial with and driven by said fan at a velocity

greater than that of the fan by means of gearing, a cylindrical supporting member for said disc enclosing said gearing and mounted between said disc and the hub member of the fan, said cylindrical supporting member having an arm pivotally secured to said tube, and a supply pipe for liquid arranged to pour liquid over said disc, said fan, supporting member and disc being mounted substantially coaxially inside said tube with their axes parallel with the axis of the tube, and said hub member, supporting member and disc being of the same external diameter and together forming a substantially cylindrical body which provides between itself and the internal surface of the tube a substantially annular space for the air to pass through.

2. Apparatus as specified in claim 1 wherein said disc is mounted on a spindle journaled in the cylindrical supporting members and having a driven wheel thereon, and a second wheel is journaled on the supporting member between the driven wheel and an internal surface of said hub member, said driven wheel; second wheel and hub comprising the gearing.

3. An apparatus for humidifying air comprising: an open ended tube having a propelling fan and motor located therein; said fan having a hub portion and an annular flange surrounding said hub portion and extending substantially coaxially therefrom; a cylindrical sleeve in said tube of substantially the same diameter as the flange; a water distributing disc journaled in said sleeve and substantially the same diameter as the sleeve with the periphery thereof axially spaced from the sleeve; means for supplying liquid to said disc; gearing within said sleeve supported thereby and driven from said fan to drive the disc at a greater speed than the fan, whereby a substantially annular air space is provided between the sleeve and tube for passage of an air stream and into

which space liquid is sprayed by the disc transversely of the air stream, and an arm yieldingly secured to said tube extending across the annular space and carrying said sleeve.

5. An apparatus as specified in claim 3 wherein said arm is biased in one direction by an adjustable spring.

6. An apparatus for humidifying air comprising: an open ended tube having a propelling fan and motor for driving air through the tube, said fan having a hub portion surrounded by impelling blades and an annular flange extending from and surrounding said hub; an arm yieldingly carried by said tube; a sleeve carried by said arm in substantially axial alignment with said flange, said sleeve being of substantially the same diameter as said flange; a shaft journaled in and extending from said sleeve, said shaft carrying a water distributing disc at one end and a driven wheel at its other end; an intermediate wheel engaging said flange and driven wheel; a shaft pivotally carried in said sleeve and journaling said intermediate wheel; and means for supplying liquid to said disc.
